Atty.

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

OIL-PUMPING SYSTEM.

Application filed June 28, 1917. Serial No. 177,603.

To all whom it may concern:

Be it known that I, JOHN OLIPHANT, a citizen of the United States, residing at Chicago, in the county of Cook and State of Illinois, have invented certain new and useful Improvements in Oil-Pumping Systems, of which the following is a full, clear, and exact specification.

My invention relates to oil pumping systems.

It has for its object to pump oil or similar material in an improved manner. A further object is to provide improved means whereby gas is obtainable from the oil and utilized in the operation of the pumping system, or made available for other purposes. More specifically, my invention has for its object to provide an improved oil pumping system of the air lift pump type wherein gas is liberated from the oil and supplied to the compressor, the excess gas being supplied as fuel to the compressor driving unit, or supplied to a gasoline extracting system, both means of utilizing the excess gas being available when desired.

In the accompanying drawings, I have shown for purposes of illustration, one embodiment which my invention may assume in practice, illustrating my improved system diagrammatically in plan, the booster, however, being shown in vertical section and enlarged to facilitate illustration.

In this illustrative construction, it will be noted that I have shown a compressor 1 adapted to compress either air or gas, and connected through a suitable connection 2 with a receiver 3 which is in turn connected through a pipe connection 4 having a valve 5 therein, with the down pipe 6 of a suitable air lift pump (not shown) disposed in the well. As in the usual air lift system, the air admitted through the pipe 6 is mixed by the pump with the oil in the well and the mixture is carried up through an outside pipe 7 into the booster casing 8, wherein the mixture strikes against an umbrella top 9, the oil after passing underneath a baffle plate 10 passing out through a discharge pipe 11, while the air passes out through a controlling or escape valve 12 of any suitable type, herein connected through a pipe 13 to the intake of the compressor.

By applying such an air lift system to

pumping oil, I find that the air which is propelled through this circuit from the compressor, into the well, and back again into the intake of the compressor, gradually becomes charged with the gas thrown off from the oil until the air has been eliminated and the gas remains as the compressible element. Further, I find that as the gas comes in contact with the oil over and over again, it accumulates in a volume greater than is necessary to do the work of pumping. I have accordingly provided means whereby the excess gas may be utilized. Obviously, the means whereby these improved results may be obtained may assume various forms. In my illustrative construction, however, it will be noted that a pipe connection 14 is made to the pipe 13 through an open three-way T-joint 15, and that this connection 14 leads to a suitable reservoir or tank 16 in which the excess gas may be collected. If desired, suitable connection, preferably including this tank, may also be made, as through a pipe connection 17, with the intake of a suitable gas engine 18 operatively connected to and driving the compressor 1. Thus, it will be noted that any excess gas flowing through the connection 14 may be collected in the tank or, if desired, passed to the intake of the gas engine 18, in such a manner as to supply the fuel necessary to drive the latter and operate the system.

If desired, the excess gas, instead of being supplied to the gas engine 18, may be supplied, preferably from the tank 16, through a pipe connection 19, to a gasoline extracting system, herein indicated by the compressor 20, in order to extract the gasoline therefrom in a well known manner, such an arrangement being desirable in those installations wherein the compressor 1 is driven by steam or electricity. In working upon oil rich in gas, however, I prefer to drive the compressor by a gas engine, as by the utilization of such an engine it is possible to make the pumping system supply its own fuel and at the same time to extract gasoline from the remainder of the excess gas, thereby causing the system to operate at the greatest efficiency. While in certain instances, the use of a tank such as the tank 16 may be unnecessary, the same is, however, also usually used in view of its storage capacity and its steadyng effect upon the

supply. Obviously, in the use of such a system any desirable valves, such for instance as the hand operated valves 21, 22, and 23, may be provided at suitable points 5 in the system, as, for example, in the several pipe connections of the tank, in order that any desired element or elements may be cut out of operation, and, if desired, suitable check valves may also be provided to prevent 10 back flow, a check valve 24, for example, being provided in the connection between the tank and the engine. As usual, a suitable valve 25 may also be provided in the pipe connection 13 in order to cut out 15 the gas utilizing system, the booster escape valve 12 then being made to exhaust to the atmosphere in a well known manner.

In the use of my improvement, it will be noted that the system is capable of being 20 operated at a relatively low operating pressure, a feature highly desirable in pumping oil, and that the well known advantages arising from the utilization of gas instead of compressed air as the compressible element 25 in the compressor, are obtained. Attention is also directed to the fact that, due to the provision of the booster, it is possible to deliver the oil through a horizontal line to a surface tank without the provision 30 of separate lifting pumps. It will also be evident that a plurality of wells may deliver into a common main communicating with the discharge pipes 11, and that a plurality of wells may be operated, when desired, from 35 one compressor or central power plant, it only being necessary to connect a plurality of lines to the receiver 3 at the power plant. This power plant, it will also be observed, instead of wasting the gas through discharging 40 the same to the atmosphere, also acts to supply its own fuel and at the same time, when the oil is rich in gas, acts to extract the gasoline from the excess oil in such a manner as to produce an exceedingly 45 valuable by-product, all of the gas being utilized in one form or another.

While I have in this application specifically described one embodiment which my invention may assume in practice, it will be understood that this form of the same is shown herein for purposes of illustration and that the invention may be modified and assume various other forms without departing from its spirit, it being my intention to 55 include all such modifications within the scope of the appended claims.

What I claim as new and desire to secure by Letters Patent is:

1. In an oil pumping system, in combination, oil pumping mechanism including mechanism for liberating gas from the oil, and means for utilizing the liberated gas to operate the system.

2. In an oil pumping system, in combination, pressure fluid lift mechanism includ-

ing a compressor and a booster connected thereto, a gas driven power unit, and means for supplying gas thereto from said booster.

3. In an oil pumping system, in combination, pressure fluid lift mechanism including a compressor and a booster connected thereto, a storage tank for gas not required in the pumping circuit, and means for supplying gas thereto from said booster. 70

4. Oil pumping mechanism comprising pressure fluid lift mechanism including a compressor and a booster connected thereto, a gasoline extracting unit, and means for supplying a variable portion of the gas from said booster to said unit. 75

5. In an oil pumping system, in combination, pressure fluid lift pumping mechanism including a compressor and a booster connected thereto, and means for supplying a portion of the gas-laden exhaust from the booster to the compressor intake. 80

6. In an oil pumping system, in combination, a compressor, operatively connected mechanism for lifting oil and separating gas therefrom, and means for utilizing the gas 90 liberated from the oil to operate the system including a connection between said separating mechanism and said compressor.

7. In an oil pumping system, in combination, pressure fluid lift mechanism including a compressor and a booster connected thereto, a connection between the booster exhaust and the compressor intake, and means for drawing off the excess gas from said connection. 95

8. In an oil pumping system, in combination, pressure fluid lift mechanism including a compressor and a booster connected thereto, a connection between the booster exhaust and the compressor intake, a gasoline 105 extracting unit, and a connection between the same and said connection.

9. In an oil pumping system, in combination, pressure fluid lift mechanism including a compressor and a booster connected thereto, means for utilizing the liberated gas as the compressible element in said compressor, a gas driven motor unit for said compressor, and means for supplying a portion of said gas to said unit. 110

10. In an oil pumping system, in combination, pressure fluid lift mechanism including a compressor and a booster connected thereto, means for utilizing the liberated gas as the compressible element in said compressor, 120 a gasoline extracting unit, and means for supplying a portion of the gas to said unit.

11. In an oil pumping system, in combination, pressure fluid lift pumping mechanism including a compressor and a booster connected thereto, means for supplying the gas-laden exhaust from the booster to the compressor intake, a gas engine driving said compressor, and means for supplying gas thereto from said booster. 125

12. In an oil pumping system, in combination, pressure fluid lift pumping mechanism including a compressor and a booster connected thereto, means for supplying the gas-laden exhaust from the booster to the compressor intake, a gas engine driving said compressor, and means connected to said first mentioned means for supplying gas thereto from said booster.
13. In an oil pumping system, in combination, pressure fluid lift mechanism including a compressor and a booster connected thereto, a connection between the booster exhaust and the compressor intake, a reservoir connected to said connection, a gas driven compressor driving motor, a gasoline extracting unit, and connections between each of said last mentioned elements and said reservoir.
14. In an oil pumping system, in combination, pressure fluid lift mechanism including a compressor and a booster connected thereto, a connection between the booster exhaust and the compressor intake, a reservoir connected to said connection, a gas driven compressor driving motor, and a connection between said driving motor and said reservoir.
15. In an oil pumping system, in combination, pressure fluid lift mechanism including a compressor and a booster connected thereto, a connection between the booster exhaust and the compressor intake, a reservoir connected to said connection, a gasoline extracting mechanism, and a connection be-
- tween said extracting mechanism and said reservoir.
16. In an oil pumping system, in combination, pressure fluid lift mechanism including a compressor and a booster connected thereto, means for utilizing a portion of the liberated gas as the compressible element in said compressor, a gas driven motor unit for said compressor, means for supplying a portion of said gas to said unit, a gasoline extracting unit, and means for supplying a portion of the gas to said last mentioned unit.
17. In an oil pumping system, in combination, an air lift system comprising a gas circuit including a compressor, a down pipe, a pump, a booster, and a return pipe from the booster to the compressor, a gas driven power unit, a gasoline extraction unit, and means for directing a flow of gas from the return pipe to either the power unit or the extraction unit.
18. In an oil pumping system, in combination, an air lift system comprising a gas circuit including a compressor, a down pipe, a pump, a booster, and a return pipe from the booster to the compressor, a gas driven power unit, a gasoline extraction unit, means for directing a part of the flow through said return pipe to said power unit, and means for directing excess gas to said extraction unit.

In testimony whereof I affix my signature.

JOHN OLIPHANT.
